H. S. HASSELQUIST

PENCIL

Filed June 4, 1921

FIG. 1

FIG. 3

FIG. 4

FIG. 2

FIG. 5

Inventor:

Hugo S. Hasselquist

H. S. Hasselquist

UNITED STATES PATENT OFFICE.

HUGO S. HASSELQUIST, OF CHICAGO, ILLINOIS, ASSIGNOR, BY MESNE ASSIGNMENTS, TO AUTOPOINT MANUFACTURING COMPANY, OF CHICAGO, ILLINOIS, A CORPORATION OF ILLINOIS.

PENCIL.

Application filed June 4, 1921. Serial No. 474,948.

To all whom it may concern:

Be it known that I, HUGO S. HASSELQUIST, a citizen of the United States, residing at Chicago, in the county of Cook and State 5 of Illinois, have invented certain new and useful Improvements in Pencils, of which the following is a specification.

This invention relates to a pencil in which is slidably held a lead that is adapted to be 10 advanced into writing position by means of any suitable propelling device; more particularly it is concerned with certain improvements in the pencil tip which is formed to engage frictionally with the lead so as to 15 hold the same against slipping.

In the manufacture of lead pencils, such, for instance, as those disclosed in the Keeran Patent No. 1,372,354 granted March 22, 1921, the requirements of dimensions, materials, etc., impose certain conditions which 20 present special difficulties. Among the various parts which commonly prove troublesome is the pencil tip which engages the lead by exerting thereon a spring pressure of a 25 kind and degree to afford proper support to the lead. According to the present construction, the tip avoids marring or splitting the lead and is formed to present a desirable area of bearing surface to the lead in 30 a manner which will reduce to a minimum the likelihood of its breakage.

In the accompanying drawing an embodiment of my pencil tip is shown in the manner following:

35 Figure 1 is a longitudinal section through the lower end of a pencil equipped with my friction tip;

Fig. 2 is an end elevation thereof, the lead being shown in cross section;

40 Fig. 3 is an enlarged fragmentary elevation of the lower end of the tip, as it appears when the slits are first formed;

Fig. 4 is a similar view showing the slits after being closed; and

45 Fig. 5 is a similar view showing the tip expanded as when a lead is held therein.

Referring to Fig. 1, I have shown the lower or pointed end A of a pencil within which is arranged a guide tube B for the lead C, the lower end 6 of the tube being

threaded to connect with a pencil tip E of metal which is produced from a suitable spring material. Preferably the outer walls of the tip are tapered to align and lie flush with those of the pencil body, as shown. 55

There is formed within the tip a chamber 7 which extends from below the tube end for perhaps half its remaining length, and also a cylindrical bore 8 which proceeds from the chamber through to the tip extremity. As shown in Fig. 1, the walls surrounding the tip bore taper outwardly slightly commencing with a point 9 about midway of the length of the bore so as to recede thereabove as at 10 from the lead C 60 that is projected therethrough. From this it results that the lead is engaged only throughout the lower portion of the tip whose walls are adapted to exert a spring pressure against the lead. Radial slits 11, 70 three being the preferred number, are formed clear through the walls up to about the point 9 and thereabove decrease in depth, as viewed from the tip exterior, so as to cease altogether at about the point 12 which 75 is in the region of the lowermost portion of the chamber 7. By forming slits such as these, three spring sections a, b, and c are provided (see Fig. 2), each of which frictionally engages the lead throughout a substantial portion of its length. 80

In the formation of these slits, it is most convenient to use rotary saws having a thickness of perhaps .010". As these slits, so formed, are considerably wider than necessary, the tip is swedged so as to force together its several spring sections, thereby closing the slits, as shown in Fig. 4, so that no discernible gaps exist. In this condition a lead of perhaps .0465" diameter is projected through the tip whose internal diameter below the point 9 is very slightly less. When the lead is so introduced, the several tip sections will be slightly expanded to permit a relationing of the parts as shown in 85 Figs. 1 and 5. It will be noted in the former figure that the lead is engaged by each section of the tip throughout that portion of its length which lies below the point 9. This affords a bearing surface of appreciable 90 95 100

length such that the resulting pressure upon the lead will be distributed over a considerable area.

I claim:

- 5 In a pencil, the tip portion having an axial bore, the extremity of the tip portion being slitted to provide resilient sections, the bore at the slitted portion being slightly tapered in the absence of the lead and the

slitted portion being adapted to be expanded 10 by the insertion of a lead so that the bore at the slitted portion is substantially cylindrical and bears against the lead throughout substantially the entire area of the slitted portion.

HUGO S. HASSELQUIST.
